UNITED STATES PATENT OFFICE.

WILLIAM H. ALLEMAN, OF INGALLS, MICHIGAN.

ATTACHMENT FOR GAS ENGINES.

Application filed July 2, 1926. Serial No. 120,180.

This invention relates to the air-supply of gas-engines and has for its object the provision of a simple device which may be easily applied to an engine and by the use 5 of which additional air may be supplied to the engine to dilute the explosive mixture, reducing the consumption of fuel without any loss of efficiency in the engine. One embodiment of the invention is illustrated in the accompanying drawing and 10 will be fully described, the novel features being particularly pointed out in the appended claims.

In the drawing, Figure 1 is an elevation 15 of a conventional carbureter and cam shaft and a portion of the intake manifold of an internal combustion engine.

Figure 2 is an enlarged plan view, with 20 parts in horizontal section, of the central portion of the cam shaft,

Figure 3 is a longitudinal section of the central bearing of the cam shaft,

Figure 4 is a view similar to Fig. 3 but showing the parts in a different position,

25 Figure 5 is a transverse section on the line 5—5 of Fig. 3.

Figure 6 is a transverse section on the line 6—6 of Fig. 4.

The reference numeral 1 denotes the 30 intake manifold, 2 the carbureter, and 3 the cam shaft of a four-cycle automobile engine, although it is to be understood that the invention may be applied to other engines.

35 In the practice of my invention, as illustrated, longitudinally extending grooves or recesses 4 are formed in the central bearing 5 of the cam shaft and spaced equi-distantly around the bearing, there being a groove 40 or pair of grooves for each cylinder of the engine. In the specific construction illustrated, the grooves are arranged in pairs, the members of each pair being alined longitudinally of the bearing and separated 45 by a thin lip or spur 6 with the end surfaces of the grooves concave to properly direct the air currents flowing over them. The dividing lip 6, however, may be omitted and a single groove substituted for a pair 50 of grooves, and, instead of a groove or mere surface opening, the air channel may be produced by boring entirely through the bearing or shaft, especially when applying the invention to existing engines. Fitting 55 closely about the bearing 5 is a sleeve 7 which may be fastened to the engine block

or otherwise secured, and through the wall of this sleeve are formed openings 8 near its ends and a central opening 9, a pipe 10 leading from the central opening into 60 the trunk of the manifold above the carbureter, as shown in Fig. 1. The openings 8 and 9 are all on the same longitudinal line of the sleeve so that, as the grooves 4 are brought successively to the openings, 65 communication will be established between the end openings and the central opening and a current of air will be directed into the pipe 10. A cut-off valve 11 of any 70 approved construction is inserted in the pipe 10 and is controlled by a rod 12 extending to the instrument board of the vehicle so that flow through the pipe 10 may be regulated according to the judgment of the chauffeur. The pipe 10 may be secured to 75 the engine block or otherwise held against displacement.

It is well known that in cold weather or when starting the engine a richer fuel mixture is required than is needed after the 80 engine gets warm or when running at a high speed but, as frequent adjustment of the carbureter is inconvenient and often troublesome, the carbureter is left in one adjustment, the result being that after the 85 engine has been running some time more fuel is drawn into the cylinder than is needed and this surplus fuel is an economic loss. My invention enables the chauffeur to save 90 this fuel and thereby reduce the cost of running the car. The openings 8 and 9 may be set so as to take in air from the inside or outside of the motor enclosure but the grooves or chambers 4 are so disposed that when any groove or chamber is in communication with the pipe 10 the piston in the 95 corresponding cylinder will be on the last half of its intake stroke. When the piston is entirely down, the cam shaft closes the openings 8 and 9, as shown in Figs. 4 and 100 6, and will keep them closed until the next piston has made one-half of its intake or suction stroke at which instant the succeeding grooves 4 will be brought into alinement with the openings, as shown in Figs. 105 3 and 5, whereupon additional air will be admitted to the cylinder which is charging without disturbing the adjustment of the carbureter. When the valve 11 is open, the first half of the suction stroke of the piston 110 draws in fuel and during the last half of the stroke air is drawn over the gas to fill

the cylinder. When the ensuing explosion occurs all the gas is burnt without any coking and all needed power is generated. Whatever may be the load or speed, complete combustion will be effected.

Having fully described my invention what I claim as new and desire to secure by Letters-Patent, is:—

- 10 1. An attachment for explosive engines comprising a pipe extending from the cam shaft to the intake manifold, and means at and controlled by the cam shaft for periodically admitting air to the pipe.
- 15 2. An attachment for explosive engines comprising a pipe extending from the cam shaft to the intake manifold, a sleeve around the cam shaft in direct communication with the pipe, said sleeve having openings spaced from the pipe, and means on the cam shaft to periodically establish communication between said openings and the pipe.

3. An attachment for explosive engines comprising a sleeve fitting closely around the cam shaft and having a plurality of longitudinally alined openings, means on the cam shaft to periodically establish communication between the openings, and a pipe leading from the central opening to the intake manifold of the engine.

4. An attachment for explosive engines 30 comprising a cam shaft bearing having equidistantly spaced chambers in its circumference, a sleeve fitting closely about said bearing and having a series of longitudinal openings through its wall to be periodically 35 placed in communication by a chamber in the cam shaft bearing, and a pipe leading from one of the openings to the intake manifold of the engine.

In testimony whereof, I have signed this 40 specification.

WILLIAM H. ALLEMAN.
